UNITED STATES PATENT OFFICE.

HARRY W. SMITH, OF NEWARK, NEW JERSEY.

ELECTRIC RAILWAY.

SPECIFICATION forming part of Letters Patent No. 399,091, dated March 5, 1889.

Application filed September 14, 1888. Serial No. 285,400. (No model.)

To all whom it may concern:

Be it known that I, HARRY W. SMITH, a citizen of the United States, residing at Newark, in the county of Essex and State of New Jersey, have invented certain new and useful Improvements in Electric Railways; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to simplify the construction and reduce the cost of electric railways; to render the same more durable; to more perfectly prevent moisture from affecting the working parts of the conducting media, so as to limit or obstruct the passage or flow of electricity to the car or to the motor thereon; to enable a leak, should one occur in the conduit, to be more quickly and easily detected, and, generally, to secure a more perfect and efficient railway.

The invention consists in the improved electric railway and in the combinations and arrangements of parts thereof, substantially as will be hereinafter set forth, and finally embodied in the clauses of the claim.

Referring to the accompanying drawings, in which like letters of reference indicate corresponding parts in each of the several figures of the three sheets, Figure 1 is a side elevation of a car arranged on an electric railway, (shown in central vertical longitudinal section,) showing the relation of said car to said railway. Fig. 2 is a plan of the said railway. Fig. 3 is an enlarged sectional view taken on line *x*, Fig. 2; and Fig. 4 is a sectional view illustrating the arrangement of the car and the rails with the conduit. Figs. 5 and 7 are central longitudinal sections of the track or way, showing modifications of construction; and Fig. 6 is an enlarged detail section showing the preferred construction. Fig. 8 is a sectional view illustrating in detail the construction of the contact-plates and the means of packing the same. Fig. 9 is a plan of the same, indicating certain openings. Figs. 10 and 11 are enlarged sections through lines *y* and *z*, respectively; and Fig. 12 illustrates a

modification of the arrangement of the magnets.

In said drawings, *a* indicates a car having an electric motor thereon, which latter may 55 be of any usual or suitable construction.

b b indicate suitable rails for the wheels of said car, and *c* indicates a conduit, way, or longitudinal receptacle or passage for one or more conducting-wires or equivalent conductors for the electric fluid by which the car is impelled. Said conduit, way, receptacle, or passage also serves as a sealed or impervious tube or passage for dry air, by means of which the said conduit may be kept free from moisture by evaporation, the said air being forced through said conduit by means of a suitable blower, exhauster, or other air-impelling equivalent device, *d*, arranged at one end of the conduit or at any convenient point in its 70 length. The said conduit is preferably laid midway between the rails, although it may be laid in any other convenient position, and is preferably constructed of wooden posts or stringers *e*, arranged end to end and longitudinally grooved on the upper side to form a continuous passage-way, *f*, for the conducting media and to form a chamber through which air may be forced. The said conduit is or may be incased in metal *g*, as in Fig. 10, 80 to prevent the wood from absorbing moisture, and thus in time rotting, although it may be incased or coated with tar or other impervious material or matter.

At the top the chamber of the conduit is 85 covered by a series of top plates or contact-plates, *h h*, which are separated from one another to secure insulation, and are of sufficient strength and durability to resist the weight and wear and tear of ordinary street 90 traffic. The said plates serve to receive or engage a brush or contact shoe or device, *i*, forming a part of or connected with an electric motor, *J*, arranged in connection with a car. The said top or covering plates, *h*, are 95 made in short insulated sections, so that the car will cover four or more of said sections, and only those which are covered or protected by the car will be in circuit, and thus there will be no danger of any transmission of the 100 current to horses or persons traveling on the railway.

Within the chamber formed beneath the plates is arranged an electric conductor, *k*, which consists, preferably, of a continuous strip of metal disposed at the bottom of said chamber. Between the said conductor and said plates is arranged a series of armatures, *l*, adapted to be acted upon by magnets arranged on the under side of the car to connect the conductor *k* with the insulated plates

10 *h*. Said armatures are preferably in the form of levers *m*, as in Fig. 6, and are adapted to be raised at one end and lowered at the opposite end, so that the connections are broken at two places simultaneously, to reduce the

15 liability to produce a spark or to form an arc. When the armature is in contact with the plates *h*, and at the bottom end the lever or brush or spring thereon is in contact with the conductor *k*—a position which is only attained

20 when the car containing the magnets is over said plates and in a position to draw upon the armature—then the electric current is closed from the battery or dynamo to the motor on the car, and the said car is propelled. The 25 current leaving the motor *j* may be grounded or returned through a conductor in the conduit.

The armatures within the conduit may be simple plates or strips, as indicated in Figs. 30 5 and 7, which are pivoted so as to lie permanently in contact with the conductor and against one another, or other modifications of construction may be employed without departing from this invention.

35 To prevent more effectually the escape of air from the conduit, or to allow of the air being forced through the air chamber or passage, so as to take up moisture therefrom and thus keep the interior conduit practically dry,

40 I preferably arrange a packing, *n*, of suitable material, between the plates and the grooved body of the conduit, as indicated in Figs. 8, 10, and 11, said packing breaking joints with the series of plates and extending across the 45 top of the chamber or passage. Openings *n*², as indicated in Fig. 9, are provided where it is intended that the armatures shall engage the plates *n*² to allow for such engagement.

Beneath the packing and the joints between 50 the plates *h*³ may be arranged a suitable bridging to support the packing or the insulating material *h*⁴ between the plates.

At one end of the conduit may be arranged the blower or exhauster *d*, for forcing the air 55 through the chamber or passage. Other suitable means may be employed for the same purpose.

Should a leak occur, the same may be detected by introducing an odoriferous substance—such as oil of peppermint—into the chamber, the odor of which escaping through the leak will enable the workmen to identify its position. When the armatures are, in connection with the lever, made of fibrite or 65 wood or such like material, I may introduce a tube, *o*, as indicated in Fig. 6, and through the same insert a fulerumal bar, *p*, which

may be round or pointed, to reduce friction. The upper end of the lever is made to slightly overbalance the other parts to keep said lever 70 in normal disengagement from the plates. A stop, *r*, may be employed to limit the movement of the lever. The springs or brushes *s* on said lever are employed to secure a scraping contact with the conductor and the 75 plates.

I do not wish to limit myself to any form or kind of conductor, and various changes may be made in the other parts without departing from the invention.

80

The magnets on the car, by means of which the armatures are attracted, may be fixed thereon, as in Fig. 1, or movable, as indicated in Fig. 12. In the latter case they may be attached to the belt working upon the wheel- 85 journal or pulleys thereon, so as to remain longer over the armatures, and thus be more effective in attracting them, thereby allowing of a greater speed to the car.

In operation, as the car moves along the 90 track, the armatures are successively attracted by the magnets. A circuit is thus continually kept closed, and the motor upon the car supplied with electricity, as will be understood.

Having thus described the invention, what 95 I claim as new is—

1. The improved electrical railway having a sealed conduit provided with a conductor, an air-impelling device, *d*, contact-plates, and armatures for connecting said conductor and contact-plates, combined substantially as and for the purposes set forth.

2. The improved electrical railway herein described, combining therein a series of grooved stringers arranged to form a continuous conduit, a series of contact-plates arranged on the top of said stringers and insulated from one another, a series of armatures, a conducting-wire arranged in the groove of said stringers, and a packing or filling for insulating said contact-plates and sealing the conduit, substantially as and for the purposes set forth.

3. The improved electrical railway herein described, combining a longitudinally-grooved 115 stringer, a series of insulated plates covering said groove and packed or sealed, and forming, with said stringer, a closed conduit, a conducting-wire arranged at the bottom of said groove, levers having armatures thereon arranged in said groove over said conducting-wire, and a packing or filling for sealing or closing the openings between said plates to provide an impervious passage in said stringer, substantially as set forth.

4. The improved electric railway combining therein stringers having a continuous passage therein open to allow air to be forced therethrough, plates *h* *h*, secured on said stringer, covering the groove or passage therein 130 and insulated from one another, armatures, and a conductor, substantially as and for the purposes set forth.

5. In combination, in an electric railway,

125

stringers having a passage, *f*, plates *h h*, a conductor, *k*, levers *m*, having an armature, *c*; and springs or brackets *s*, electrically connected, and stops *r*, all arranged and operating substantially as set forth.

6. The improved electric railway having a conduit, with a conductor and a series of armatures therein, and a series of non-magnetizable plates, *h h*, adapted to be engaged by said armatures and transmit the electric current to the car, substantially as and for the purposes set forth.
7. The improved electric railway having a

conductor and a series of non-magnetic plates, and armatures interposed therebetween and adapted to connect the same when influenced by a magnet of a car, substantially as and for the purposes set forth.

In testimony that I claim the foregoing I have hereunto set my hand this 13th day of September, 1888.

HARRY W. SMITH.
